DESIGN FOR A RADIATOR OR SIMILAR ARTICLE

Mikolaj Stefanczyk, Hamtramck, Mich.

Application November 16, 1935, Serial No. 59,603

Term of patent 7 years

To all whom it may concern:

Be it known that I, Mikolaj Stefanczyk, a citizen of the United States, residing at Hamtramck, in the county of Wayne and State of Michigan, have invented a new, original, and ornamental Design for a Radiator or Similar Article, of which the following is a specification, reference being had to the accompanying drawing, forming part thereof.

Figure 1 is a side elevation of a radiator or similar article, showing my new design.

Figure 2 is a top plan view of the radiator shown in Figure 1.

Figure 3 is an end elevation of the radiator shown in Figure 1.

I claim:

The ornamental design for a radiator or similar article, as shown.

In testimony whereof I affix my signature.

MIKOLAJ STEFANCZYK.
